UNITED STATES PATENT OFFICE.

ROBERT H. F. SEWALL, OF SHREVEPORT, LOUISIANA.

COMPOUND FILE.

1,290,371.

Specification of Letters Patent.

Patented Jan. 7, 1919.

Original application filed May 19, 1917, Serial No. 169,672. Divided and this application filed April 26, 1918.
Serial No. 230,878.

To all whom it may concern:

Be it known that I, ROBERT H. F. SEWALL, a citizen of the United States, residing at Shreveport, in the parish of Caddo and State of Louisiana, have invented certain new and useful Improvements in Compound Piles; and I do hereby declare the following to be a full, clear, and exact description of the invention, such as will enable others skilled in the art to which it appertains to make and use the same.

My present invention relates to improvements in compound piles especially adapted for use when driving in deep water, and more especially for driving in deep running water, and for combining with other similar piles to form a practically water-tight wall whereby a jetty, or dam, or retaining wall, or a face for same is secured.

It has been found in practice in driving ordinary wooden piles in deep water, and especially where there is a swift current to the water, that the lower end of the pile tends to swing with the current, and there is great difficulty in driving the pile in a vertical direction, and more especially in locking the same onto adjoining piles.

Various means for weighting the pile have been adopted, but none of which, as far as I am aware, has proved entirely satisfactory; moreover with such piles long and expensive timbers are required.

According to my present invention I provide a compound pile made partly of timber and partly of reinforced concrete held within said timber, whereby the weight of the concrete causes the pile to sink readily, and whereby smaller and shorter sticks of timber may be used.

The hereinafter described form of pile is especially adapted for use in the pile driving apparatus illustrated and described, but not claimed, in my Patent No. 1,267,129, granted May 21, 1918, and entitled Improvements in apparatus for driving piles.

My invention will be more clearly understood after reference to the accompanying drawings, in which:

Figure 1 shows a cross section through the bed of a stream, with a series of interlocking piles driven partly across the same.

Fig. 2 shows a side elevation of a compound pile made of wooden framework, with a concrete core held in the center thereof, parts being broken away.

Fig. 3 is a plan view of the pile shown in Fig. 2, with adjacent and interlocking piles indicated in dotted lines; and

Fig. 4 shows the wooden framework and reinforcing spikes before the concrete is poured in.

In the form of pile herein shown, there are two wooden side beams A and A', which may be of a single piece or built up of several pieces, if desired, which are spaced as shown and are connected together by tie spikes B, and which also serve as reinforcements for the concrete; and into the spaces between these bolts shorter spikes C are driven, which also serve to hold the concrete after it is poured in.

On the inner walls of each side piece A and A' I preferably provide a series of notches or sockets a, into which the concrete flows and sets, and thus serves to further bind the parts together.

On the outer edge of one of the timbers A, I provide a dovetail tenon piece D, bolted to the member A, and on the outer edge of the opposite member A' I provide two guide pieces E having overhanging edges e adapted to engage the dovetail member D of the adjoining pile, as shown in dotted lines in Fig. 3.

If it is desired to use hydraulic pressure in the driving of the pile, a pipe F (see Fig. 3) may be provided, which pipe carries the water jet, not shown, under pressure to the bottom of the pile, and washes away the sand or mud beneath the same as the pile is being driven.

This pipe F may be permanently attached to the pile, or may be in the form of a hose which is inserted into or removed from the groove a° in the pile, as shown in Fig. 3.

After the frame of the pile has been prepared, as shown in Fig. 4, the said frame is laid flat on its side on any flat floor, and concrete G is poured into the channel between the parts A and A', and when this concrete has sufficiently hardened the pile is ready for use.

It will be seen that the bolts B and C serve to reinforce this concrete and at the same time hold all the parts of the pile together, and furthermore the concrete flowing into the sockets a will become anchored to the timbers A and A' of the pile, and thus the structure will be more firmly bound together.

The use of the concrete increases the specific gravity of the pile, so that there will be no tendency of the same to float in the water, which is a source of great trouble where 5 long piles are being driven in deep water, as already set forth.

By this construction a heavy and durable pile is produced, all parts of which may be carried separately to the spot where the pile 10 is needed and there assembled, and thus there is a great saving of expense, not only in manufacture, but in transportation.

For driving in deep water a suitable cap and follower, such as is described in my application Serial No. 169672 aforesaid, may be used; but these not being a part of my 15 present invention will not be further described herein.

It will be seen that with this form of compound pile the wooden side members protect the concrete core incident to the operation of driving, and the pile will require no cushion block, as is the case with the well known concrete pile; moreover this concrete 25 core protects the timber, and together with the tie spikes it prevents the timber from splitting or brooming while together they impart the desired weight to the pile to overcome buoyance and furnish the requisite 30 strength, toughness and resiliency to stand ordinary driving.

After one pile is driven, the adjacent pile is connected thereto having its tongue engaging the dove-tail groove in said pile, 35 then this adjacent pile is driven and followed down to the desired depth, as shown in Fig. 1. In ordinary work the head of the last pile inserted is generally at or near the water surface where the foreman can see to 40 properly insert the dovetail tongue in the groove; but when driving in deep swift flowing current where it is necessary to follow the head of the pile down below the surface of the water to near the bottom of the river 45 as required in works of bank protection and, as shown in Fig. 1, the last pile is left standing above the surface of the water, the buck on the pile driver raised until the head block permits the pile driver moved forward, a 50 follower is then placed on the head of the pile preceding the last pile, the hammer is lowered on the follower and the pile driven home. The driver is then pulled back to its proper position and another pile is entered. 55 However, these compound piles can be made with the ordinary tongue and groove and where the current is not too swift, they can be lowered and forced in proper position from the front by the use of my improved 60 pile driver with the buck attachment, as all described in my application Serial No. 169,672 aforesaid.

By using a series of piles of the character herein described a continuons substantially 65 water-tight wall may be constructed leading

out from the top of the bank into the stream and across the channel up to the top of the bank on the opposite side, without interfering with the flow or navigation of the stream while the work is being done; coffer dams, 70 retaining walls and the like can be constructed without the cost and labor of excavations, not excepting sea walls, and foundations for locks, etc.

It will be obvious that various modifications might be made in the herein described construction, and in the combination and arrangement of parts which could be used without departing from the spirit of my invention. 75

Having thus described my invention what I claim and desire to secure by Letters Patent of the United States is:

1. A compound pile consisting of two timbers spaced apart and connected together by 80 bolts, with concrete molded in the space between said timbers and surrounding those portions of the connecting bolts lying between said timbers, substantially as described. 85

2. A compound pile consisting of two timbers spaced apart and connected together by bolts, with concrete molded in the space between said timbers and surrounding those portions of the connecting bolts lying between said timbers, a strip secured to the outer edge of one of said timbers, and a pair of strips secured to the outer edge of the other timber to form a groove between the two, substantially as described. 90

3. A compound pile consisting of two timbers spaced apart and connected together by bolts, with concrete molded in the space between said timbers and surrounding those portions of the connecting bolts lying between said timbers, one of said timbers being provided with a longitudinal groove therein adapted to receive a pipe, substantially as described. 105

4. A compound pile consisting of two timbers spaced apart and connected together by bolts, with concrete molded in the space between said timbers and surrounding those portions of the connecting bolts lying between said timbers, a strip secured to the outer edge of one of said timbers, and a pair of strips secured to the outer edge of the other timber to form a groove between the two, one of said timbers being provided with a longitudinal groove therein, adapted to receive a pipe, substantially as described. 110

5. A compound pile comprising two timbers spaced apart, tie bolts between said timbers crossing the space between same, and additional bolts projecting into the space between said timbers, with concrete molded in the space between said timbers and surrounding those portions of the bolts lying between said timbers, a dovetail strip secured to the outer edge of one of said timbers, 120

125

130

bers, and a pair of strips secured to the outer edge of the other timber to form a dovetail groove between the two, substantially as described.

5. A compound pile comprising two timbers spaced apart, tie bolts between said timbers crossing the space between same, and additional bolts projecting into the space between said timbers, with concrete molded in 10 the space between said timbers and surrounding those portions of the bolts lying between said timbers, one of said timbers being provided with a longitudinal groove therein adapted to receive a pipe, substantially as described.

7. A compound pile comprising two timbers spaced apart, tie bolts between said timbers crossing the space between same, and additional bolts projecting into the space between 20 said timbers, with concrete molded in the space between said timbers and surrounding those portions of the bolts lying between said timbers, a dovetail strip secured to the outer edge of one of said timbers, and a pair of strips secured to the outer edge of the other timber to form a dovetail groove between the two, one of said timbers being provided with a longitudinal groove therein, adapted to receive a pipe, substantially as described.

8. A compound pile comprising two timbers spaced apart and each provided with oppositely disposed recesses, tie bolts between said timbers crossing the space between same, and additional bolts projecting into the space between said timbers, with concrete molded in the space between said timbers and surrounding those portions of the bolts lying between said timbers, and 35 projecting into said recesses, substantially as described.

9. A compound pile comprising two timbers spaced apart and each provided with oppositely disposed recesses, tie bolts be-

tween said timbers crossing the space between same, and additional bolts projecting into the space between said timbers, with concrete molded in the space between said timbers and surrounding those portions of the bolts lying between said timbers and projecting into said recesses, a dovetail strip secured to the outer edge of one of said timbers, and a pair of strips secured to the outer edge of the other timber to form a dovetail groove between the two, substantially as described.

10. A compound pile comprising two timbers spaced apart and each provided with oppositely disposed recesses, tie bolts between said timbers crossing the space between same, and additional bolts projecting into the space between said timbers, with concrete molded in the space between said timbers and surrounding those portions of the bolts lying between said timbers and projecting into said recesses, one of said timbers being provided with a longitudinal groove therein adapted to receive a pipe, substantially as described.

11. A compound pipe comprising two timbers spaced apart and each provided with oppositely disposed recesses, tie bolts between said timbers crossing the space between same, and additional bolts projecting into the space between said timbers, with concrete molded in the space between said timbers and surrounding those portions of the bolts lying between said timbers and projecting into said recesses, a strip secured to the outer edge of one of said timbers, and a pair of strips secured to the outer edge of the other timber to form a groove between the two, one of said timbers being provided with a longitudinal groove therein, adapted to receive a pipe, substantially as described.

In testimony whereof I affix my signature.

ROBERT H. F. SEWALL.
